UNITED STATES PATENT OFFICE.

EZECHIEL WEINTRAUB, OF LYNN, MASSACHUSETTS, ASSIGNOR TO GENERAL ELECTRIC COMPANY, A CORPORATION OF NEW YORK.

ILLUMINATING DEVICE.

1,188,121.

Specification of Letters Patent. Patented June 20, 1916.

Application filed September 12, 1914. Serial No. 861,372.

To all whom it may concern:

Be it known that I, EZECHIEL WEINTRAUB, a citizen of the United States, residing at Lynn, county of Essex, State of Massachusetts, have invented certain new and useful Improvements in Illuminating Devices, of which the following is a specification.

The present invention relates to vapor electric devices, and particularly to mercury arc lamps of the high pressure type. Its object is to obtain increased efficiency by providing means for utilizing the energy formerly wasted in a series resistance for the production of light.

15 A vapor electric lamp and particularly a high pressure lamp, such as the quartz mercury arc lamp, takes a higher current at starting than when it has assumed equilibrium and is normally operating. Therefore, if an incandescent lamp were connected permanently in series with a mercury arc lamp and proportioned to carry the starting current without damage, it will not be lighted at all or, at least, not to 20 bright incandescence when the current through the vapor lamp has assumed a normal value. If adjusted favorably for light emission at an operating current of the mercury lamp, it will burn out on starting.

In accordance with my invention, I have provided a unit comprising a vapor arc lamp, a separate resistance initially connected in series with a vapor arc lamp and proportioned to carry the high starting current of the arc, also an incandescent filament of such current rating that it will operate at normal efficiency when carrying the operating current of the arc and an automatic device for substituting the filament for the resistance after the arc has assumed equilibrium.

The accompanying drawings illustrate my invention as applied to a high pressure quartz mercury lamp.

Figure 1 illustrates diagrammatically suitable connections for carrying out the invention and Figs. 2 and 3 show a modification in which the incandescent filament is located within the envelop of a mercury vapor device.

The lamp shown in Fig. 1 comprises a refractory envelop 1, of quartz or the like, a body of mercury 2 acting as cathode during the operation of the lamp, and a coöperating

anode 3, which, in this case, consists of tungsten or other suitable refractory material.

My invention is not limited to the particular type of vapor arc lamp here shown.

A resistance 4, consisting of iron or other suitable material, is connected in series with the vapor lamp in the circuit including conductors 5, 6 and 7. In series with the resistance 4 is a switch 8 comprising contacts 9, 10 for interrupting the circuit through the resistance. An incandescent lamp 11 is connected by a conductor 12 to the anode circuit 6 of the lamp and to a movable contact 13 carried by a magnetically operated plunger 14 and coacting with a contact 15 to connect the incandescent lamp in series with the mercury arc lamp. The filament in the incandescent lamp 11 is so proportioned that it will be operated at normal incandescence when carrying the normal operating current of the arc lamp after it has assumed equilibrium. A solenoid 16, connected to conductors 5 and 7 in shunt with the lamp by a conductor 17, is proportioned to lift the plunger 14 when the voltage across the lamp has assumed the normal value.

The vapor arc is started by tilting to cause the mercury to withdraw out of contact with the anode, or by any other well-understood manner. In some cases the electrodes may be out of contact in the lamp, and, in order to strike the arc, the tilting mechanism must first tilt the lamp to cause a stream of mercury to complete the circuit through the lamp. In that case, the full line voltage is impressed across the lamp terminals before the tilting mechanism has acted. The magnet 16, therefore, might substitute the lamp for the steadyng resistance 4 too soon, and cause the lamp to burn out. To prevent this the dash pot 18 is adjusted to make the time required for the magnet 16 to act longer than the time necessary for the tilting mechanism to act.

When the lamp has started and the current has assumed a lower operating value, the voltage across the arc coincidentally rises. As soon as the voltage drop is equal to a predetermined value, lifting of the plunger 14 completes the circuit between contacts 13 and 15, thereby connecting for an instant the incandescent lamp 11 in parallel with the resistance 4 and then by raising the switch arm 8 disconnecting the re-

sistance 4. The time during which both the resistance 4 and the lamp 11 are in series with the lamp is so short that no harm is done. The plunger 14 remains in this position during normal operation of the lamp, during which time the incandescent lamp is traversed by the operating current and thus performs the double function of steadyng the arc and furnishing light.

- 10 The incandescent lamp 11, while it may be of any suitable character is preferably of the intensified type in which a refractory filament, such as a tungsten filament operates in a gas of relatively high pressure at 15 a temperature higher than the operating temperature of a vacuum lamp. As the light from the incandescent lamp is rich in red rays, it to a large extent complements the light from the vapor lamp which is rich 20 in green and blue rays and deficient in red rays. By placing both lamps in a diffusing refracting globe, a light unit of color approaching daylight may be obtained.

As shown in Figs. 2 and 3, the incandescent filament may to advantage be located within the vapor device which furnishes the gas atmosphere, in this case mercury, in which the filament operates. In Fig. 2 the arc device 19 is of the usual size and the 30 filament 20 comprises a simple relatively heavy wire of tungsten or the like operating in a side chamber 21. In Fig. 3 the filament 22 is coiled to increase the heat conservation, and the mercury arc is relatively short, its function being largely to supply 35 the mercury vapor in which the filament is operated.

I make no claim herein broadly to a lamp or other device containing a gas or vapor, 40 in which an arc is operated between suitable electrodes and having a glower of refractory material within the lamp acting as a steadyng resistance for the arc, and being heated by the arc-supporting current to a temperature 45 higher than said glower could be heated in a vacuum to have the same useful life, this combination being described and claimed in a co-pending application by George M. J. Mackay, Serial No. 861,384, 50 filed September 12, 1914.

What I claim as new and desire to secure by Letters Patent of the United States, is:—

1. The combination of means for operating an arc in mercury vapor at relatively

considerable pressure, an incandescent filament, a series resistance and means for automatically substituting said filament for at least part of said resistance when the arc-sustaining current has assumed a predetermined value. 55

2. The combination of means for operating an arc in mercury vapor, a steadyng resistance connected in series with said arc, an incandescent filament, and means substituting said filament in place of said resistance when the voltage across the arc has exceeded a predetermined value. 60

3. The combination of means for operating an arc in mercury vapor, a series connected resistance proportioned to carry the 70 starting current of said lamp, an incandescent lamp proportioned to operate at incandescence when traversed by the normal operating current of said arc, and means for substituting said lamp for said resistance 75 when the arc has assumed a stable operating condition.

4. The combination of means for operating a vapor arc including an easily vaporizable cathode and an anode, a series connected resistance proportioned to carry the starting current of said arc, an incandescent glower proportioned to operate at normal incandescence when carrying the normal operating current of said arc, and means responsive to a rise of voltage across said electrodes above a predetermined value for substituting said glower for said starting resistance. 80

5. The combination of a mercury cathode, 90 an anode, an inclosing envelop therefor, an incandescent glower within said envelop, said glower being proportioned to operate at incandescence when traversed by the operating current of an arc between said electrodes, a starting resistance for said arc, connections for including said resistance at starting in series with said arc and means responsive to a rise of voltage across said electrodes above a predetermined value for 95 substituting said glower in place of said starting resistance. 100

In witness whereof, I have hereunto set my hand this ninth day of September, 1914.

EZECHIEL WEINTRAUB.
